CONCENTRIC LINES AND CIRCUITS
THEREFORPaul D. Zottu, West Caldwell, N. J., assignor to
Radio Corporation of America, a corporation of
Delaware

Application January 21, 1937, Serial No. 121,498

3 Claims. (Cl. 178—44)

This invention relates to ultra short wave radio circuits, particularly of the concentric line type, and the associated circuits therefor. The primary object of the present invention is to provide novel constructions of concentric line tuned circuits and novel uses therefor in associated circuits.

In the accompanying drawing, Fig. 1 illustrates a concentric line tuned circuit used as an auto-transformer; Fig. 1a shows the equivalent circuit diagram for the concentric line of Fig. 1.

Referring to Fig. 1 in more detail, there is shown a concentric line tuned circuit comprising an inner conductor 1 and a concentric outer conductor 2 conductively coupled together at one end 3 and capacitively coupled together at their other end by means of a capacity plate 4 conductively connected to the inner conductor 1 and spaced from end plate 5 fastened to the end of the outer conductor 2, this concentric line being used as an impedance transforming device for radio frequencies between a suitable oscillation generation circuit 6 and a radio frequency amplifier 7. Since the oscillation generator 6 and the amplifier 7 are well known per se in the art, they will not be described in detail.

The inner conductor 1 of the concentric line consists of a threaded shaft which engages and is movable within a surrounding threaded pipe or sleeve 8 to which the input potentials from the oscillator 6 are applied through a set screw 9 which is threaded into a ring 10 surrounding the pipe 8. The shaft of the inner conductor 1 is adjustable in length by means of a suitable knob 11 which is capable of varying the capacity between the plates 4 and 5. Output energy is taken from the tuned circuit by means of a lead 12 which is conductively connected to the plate 4 of the inner conductor 1 at its upper end and which connects therewith through a suitable aperture in the end plate 5. Outer conductor 2 is provided with a suitable slit which extends over the major portion of its length for insulatingly accommodating the set screw 9 and for enabling the set screw 9 and ring 10 to be moved over the length of the pipe 8 for selection of a suitable potential point on the pipe. In this manner, it is possible to match the impedance of the energizing circuit 13 to the impedance of the amplifier 7.

In effect, the concentric line 1, 2 is an auto-transformer, as will be more readily observable upon inspection of Fig. 1a which shows the equivalent circuit diagram of the concentric line,

and wherein the input terminals correspond to the leads which connect with tank circuit 13, and the output terminals correspond to the leads which connect with amplifier 7. It will be observable, of course, that the input and output terminals might be reversed wherever desirable. The coil inductance of Fig. 1a corresponds to the uniformly distributed inductance of conductors 1 and 2, while the capacity of Fig. 1a corresponds to the concentrated capacitance between plates 4 and 5 of Fig. 1 plus the distributed capacity along the lengths of conductors 1, 2. Although terminal 12 is shown as fixed and connected in Fig. 1 to the plate 4, one may connect lead 12 to a point on conductor 1 intermediate the ends thereof so as to obtain the desired impedance match between the tuned circuit and the amplifier 7, while at the same time maintaining the desired selective characteristics of the tuned circuit.

An advantage of the tuned concentric circuit of Fig. 1 is that the length of conductor 1 can be changed by the knob 11 to obtain a desired end capacity between plates 4 and 5 without substantially disturbing the ratio of voltages between input and output terminals. This is because the total travel of inner conductor 1 is a small percentage of its total length.

What is claimed is:

1. An auto-transformer comprising a resonant concentric line having an inner and an outer conductor conductively coupled together at one end and capacitively coupled together at the other end, said inner conductor being rigid throughout its length and including a threaded conducting shaft and surrounding said shaft for the portion thereof near said one end a stationary conducting sleeve whose interior is threaded to cooperate with the threads on said shaft, a knob located externally of said resonant line and associated with said shaft for moving the same with respect to said sleeve, whereby the effective length of said inner conductor may be varied, means surrounding said sleeve and adjustable in position over the length of said sleeve for enabling a circuit connection to be made to said inner conductor.

2. An auto-transformer comprising a resonant concentric line having an inner and an outer conductor conductively coupled together at one end and capacitively coupled together at the other end, said inner conductor being rigid throughout its length and including a threaded conducting shaft and surrounding said shaft for the portion thereof near said one end a sta-

tionary conducting sleeve whose interior is threaded to cooperate with the threads on said shaft, a knob located externally of said resonant line and associated with said shaft for moving the same with respect to said sleeve, whereby the effective length of said inner conductor may be varied, a metallic ring surrounding said sleeve, said outer conductor being provided with a slot extending longitudinally thereover for enabling connection to be made to said ring.

3. An auto-transformer comprising a resonant concentric line having an inner and an outer conductor conductively coupled together at one end and capacitively coupled together at the other end, said inner conductor being rigid throughout its length and including a threaded

conducting shaft and surrounding said shaft for the portion thereof near said one end a stationary conducting sleeve whose interior is threaded to cooperate with the threads on said shaft, a knob located externally of said resonant line and associated with said shaft for moving the same with respect to said sleeve, whereby the effective length of said inner conductor may be varied, a metallic ring surrounding said sleeve and in direct contact therewith, said ring being adjustable over the length of said sleeve, said outer conductor being provided with a slot extending longitudinally thereover for enabling connection to be made to said ring at various positions over the length of said sleeve. 10 15
